BOTTLE COOLER

Robert Winter Hull and John Crawford Moore,
Connersville, Ind., assignors, by mesne assignments,
to Rex Manufacturing Company, Inc.,
Connersville, Ind., a corporation of Indiana

Application April 20, 1939, Serial No. 269,046

6 Claims. (Cl. 312—36)

This invention relates to dispensing apparatus for bottled beverages and the primary object of the same is to provide a refrigerated cabinet of the dry cooling type so constructed as to facilitate the handling and dispensing of bottled goods with a minimum of cold loss and a maximum of cooling efficiency.

Cabinets of the dry cooling automatic dispensing type are known, but as heretofore constructed have been subject to certain objections in that the dispensing mechanism was complicated and inclined to jam, the capacity of the cabinet was limited due to the room occupied by the dispensing mechanism, and other factors. The present invention is designed to provide a bottle dispensing cabinet which will overcome the foregoing and other objectionable features. The bottle dispensing mechanism operates automatically through actuation of the door of the cabinet, and due to a particular arrangement of the dispensing apparatus, the bottles removed through opening of the door are not crowded or moved out of alignment due to excess weight of bottles thereabove; maximum load capacity is provided, and the door may be opened and a bottle removed easily and quickly so that there is a minimum of cold loss; and the cabinet and coacting dispensing mechanism are arranged in a manner such as to obtain maximum cooling efficiency with a minimum number of cooling coils.

More specifically, therefore, the invention is concerned with improvements in bottle dispensing cabinets whereby the same are rendered more efficient and convenient in operation.

In the drawings:

Fig. 1 is a perspective view of a cabinet embodying the features of the invention;

Fig. 2 is an enlarged fragmentary view in transverse vertical section of the cabinet and coacting dispensing apparatus, the section being taken substantially centrally of the cabinet;

Fig. 2a is an enlarged fragmentary vertical sectional view of the end of the bottle chute and the coacting bottle receiving and transfer device carried by the door, the latter being shown open;

Fig. 3 is a view similar to Fig. 2 but taken between the nearest side wall of the cabinet and the inner casing or bottle compartment liner, and particularly showing the indexing and actuating means for the bottle dispensing wheel or magazine;

Fig. 4 is a vertical sectional view taken between the rear insulated wall of the cabinet and the inner casing or bottle compartment liner, show-

ing the latter and coacting cooling coils in rear end elevation;

Fig. 5 is a bottom plan view of said inner casing or liner taken substantially on the line 5—5, Fig. 4;

Fig. 6 is a vertical sectional view taken between the one side wall of the cabinet, and inner casing or liner, showing the latter in broken side elevation together with the coacting cooling coils;

Figs. 7 and 8 are enlarged detail fragmentary views of the bottle dispensing wheel or magazine and coacting indexing disc to better illustrate the manner of mounting the same in the cabinet;

Figs. 9 and 10 are enlarged fragmentary detail views of the door handle or latch and adjacent portions of the door and jamb;

Fig. 11 is a fragmentary view in broken front elevation of a portion of the door, particularly showing the manner of operatively connecting the indexing wheel actuating mechanism to the door.

The apparatus includes a cabinet generally indicated at C in Fig. 1, which may be made up of a plurality of individual sections or refrigerated compartments, or each section may be considered as a complete cabinet in itself. In the form shown, the cabinet is made up of a plurality of individual compartments with a separate arrangement of cooling and bottle dispensing apparatus for each section or unit; and the description and drawings will be considered as applying to each individual section of the cabinet or to the cabinet as a whole. The cabinet or each section thereof comprises an outer insulated wall 5, note particularly Fig. 2, and an inner casing or bottle compartment liner 6 which is preferably comprised of sheet metal or like material having a high ratio of thermal conductivity and is spaced from the wall 5 to provide a compartment 6a for cooling coils or analogous means. The arrangement of the cooling coils is best shown in Figs. 4, 5 and 6. The source of refrigeration is not shown but may obviously be of the mechanical type such as a motor compressor-condenser-unit or of the heat-generator absorption or any other suitable type. The line from the compressor or high pressure side of the system is indicated at 7, said line having therein heat-exchange coil 7a, and beyond this coil connecting with expansion valve 8, from which the refrigerant passes through line 9 and union 9a into a series of bottom coils 10 and 10a and then upwardly into side coils 11 and 11a, the refrigerant returning through lines 12, 12a and union

12c, note Fig. 4, and then through line 12d to the source of refrigeration. A temperature control unit 13 (Figs. 2 and 6) is mounted in a separate storage compartment 14 formed in the cabinet in a manner to be described and this unit communicates through tube 13a with a temperature control coil 13b. The expansion valve 8 is provided with capillary tube 15 (Fig. 4) which communicates with the valve through line 15a.

It will thus be seen that the inner compartment in which the bottles are disposed is cooled both at the sides and bottom, the cooling coils being located in separate compartments adjacent the main bottle storage compartment, generally indicated at 16, note Fig. 2, and shown with a plurality of bottles B disposed therein. This arrangement of coils ensures maximum cooling efficiency with a minimum of coil length and space, while the location of the control unit ensures proper regulation at all times.

The entire casing 6 is preferably suspended as a unit by means of channels 11, note Fig. 4, which are secured to the upper side walls of the cabinet and rest on ledges or shoulders 17a provided by angle members secured to the adjacent outer insulated walls as indicated at 17b. The top of the cabinet is removable to accommodate insertion and removal of the casing and coil assembly, note Fig. 6 in conjunction with Fig. 4.

Considering, now, the dispensing apparatus, the arrangement is such that when the door 18 at the front of the compartment is opened, a bottle is automatically transferred from the cooling compartment to and held on the inner face of the door within convenient reach of the party opening the door, note the position shown in Fig. 2a. The mechanism whereby this is accomplished comprises a bottle dispensing wheel or magazine generally indicated at 19, which is secured on a shaft 19a and may be formed of a series of arcuate plates welded together about a common axis to provide a plurality of magazine recesses 19b, each of which is adapted to receive a bottle and move the latter around until it reaches a gravity runway or chute 20. This runway is preferably of a length such as will accommodate a limited number of bottles but not of such length or inclination as to impose undue weight on the bottles adjacent the door and particularly on the bottle in contact with the door and which is the next to be removed when the door is opened. The bottom of the runway is provided by wall 20a which comprises part of the wall 6 and this wall 20a is curved as it approaches the back of the main storage compartment to conform to the contour of the periphery of the dispensing wheel 19 and serves to retain the bottles within the recesses 19b at this point without interposing any appreciable resistance to rotation of the wheel. The top of the runway is provided by wall 20b which wall also forms the bottom of the cold storage compartment 14. The door is hinged as at 21, and on the inner lower face thereof there is mounted a bottle transfer or delivery device 22, see Figs. 2 and 2a. This device is formed with an arcuate inner wall 22a and a shoulder 22b, and the bottom wall 20a of the runway 20 terminates in a downturned strengthening flange 20c within predetermined closely spaced relation to the arcuate wall 22a, permitting free movement of the latter when the door is swung. A bottle-retaining wall 22c is formed on the one end of the device 22, and this wall is preferably inclined and has its edge rolled to strengthen and stiffen the same.

It will be seen that as the bottles roll down the runway 20, the foremost bottle will engage in the pocket formed by the parts 22b, 22c, so that when the door is opened the foremost bottle will lie on the inner face of the door as indicated in Fig. 2a. The next bottle in the chute will roll down until it touches the inner edge of arcuate wall 22a, as shown in Fig. 2a, and all the bottles in the chute which have followed said next bottle then will be held without movement until the door is closed, whereupon they will all move slightly as the lowermost bottle rolls into the now empty pocket formed on the member 22.

The bottle-dispensing or magazine wheel 19 is preferably of a width such as to substantially span the width of the main bottle compartment, or of a width such as will prevent a bottle from falling off of the wheel or becoming cocked or misaligned. The top wall 23 of the compartment 14 provides a deflector or guide, note particularly Fig. 2. The rear wall of the main bottle compartment is provided with a deflector or guide 24. The deflector walls 23 and 24 constitute, in effect, a hopper for the bottles which guides the same into the recess 19b of the wheel 19. These members 23, 24 may be made of sheet metal or the like and are easily fabricated. The rear end wall 23a of the compartment 14 forms the adjacent side wall of the hopper, the recesses 19b of the wheel 19 being empty as they pass this point.

The dispensing wheel or magazine 19 is intermittently rotated, when the door 18 is opened and closed, through the medium of an indexing disc 25, note particularly Figs. 3 and 7, which is mounted on the end of shaft 19a carrying the dispensing wheel 19, the said disc being mounted in the coil compartment 6a. The disc is formed on its periphery with a series of cam surfaces 40 terminating in one-way teeth or notches 25a which are adapted to be engaged by the active end of gravity pawl 26 pivotally mounted on the lower end of an arm 27 which straddles the disc, the upper end of said arm being pivoted on the outer end of shaft 19a. The arm 27 has pivotally connected thereto a link 28, which extends forwardly to a point adjacent the door opening. A pivot member 29 is projected through the front end of link 28 and has mounted thereon a bearing member 29a, note Fig. 11, on which the link is directly mounted, said bearing member being formed with a flange 29b which is welded to a member 29c connected to the door. Thus when the door is opened, it pulls the link 28 forwardly, 55 and through weighted pawl 26, arm 27 and indexing disc 25, imparts a rotary step to dispensing wheel 19.

The wheel actuating mechanism including disc 25, arm 27, pawl 26 and link 28 is housed in the coil compartment 6a, and this mechanism may be installed on one or both sides of the door and operatively connected to both ends of wheel 19.

To limit the opening movement of the door, a link 30 is connected at its upper end through the medium of a slotted opening 30a with a screw or like member 30b which is anchored to the frame of the door, and at its lower end is pivotally mounted on the outer end of bearing 29a, note Fig. 11.

When the door is opened, the link 28, pawl 26 and arm 27 move from the full line position shown in Fig. 3 to the dotted line position, the pawl 26 engaging one of the teeth or notches 25a of the disc 25, imparting a partial or step rotation to the dispensing wheel 19. When the door is closed

the links 30 and 28 and pawl 26 move back to the full line position.

To prevent back or reverse rotation of the disc 25 and dispensing wheel 19, a one-way latch 31 is pivotally mounted on a stub shaft 31a adjacent the disc 25 and is provided with a pin 31b adapted to engage the teeth or notches 25a of the disc 25.

The door is provided with a handle 32 mounted on a bracket 32a anchored to the door. A latch assembly 33 is provided and is fixed in a recess formed in the inner face of the door, see Fig. 10, said assembly including a latch nib 33a adapted to engage a spring catch 34 secured in a recess 34a formed in the door frame.

From the foregoing description taken in conjunction with the drawings, the operation of the apparatus will be readily understood. The bottles may be disposed in the cabinet in horizontal position, and the entire cabinet filled to capacity. The bottle dispensing wheel or magazine 19 will be given a partial turn, or step-by-step rotation whenever the door is opened and closed; and each time this occurs, a bottle is carried around by the wheel 19 to a point where it will roll by gravity down the runway 20, the foremost bottle lying in the pocket formed by the member 22. When the door is opened the bottle is brought to the position shown in Fig. 2a within ready reach of the party opening the door and may be easily and quickly removed and the door closed. This type of dispensing mechanism will operate smoothly and surely irrespective of whether or not the cabinet is completely filled with bottles or only partially filled. This is due to the fact that the wheel 19 together with the deflector walls 23 and 24 provide in effect a feed hopper which interposes a barrier between the load of bottles and those on the gravity runway 20. As each bottle is taken from the lower end of the chute a fresh bottle is moved into gravity feed position at the upper end thereof. The apparatus will continue to function easily and smoothly down to the last bottle.

A common fault with cabinets of the type utilizing a dispensing wheel in conjunction with a feed hopper is that the bottles tend to form an arch or bridge across the opening to the dispensing wheel and jam at this point. In order to avoid any tendency towards bridging and jamming across the opening to the dispensing wheel in the present instance, said wheel is so located with respect to the hopper opening and the outer tips of the wheel so extended that said tips strike one or more bottles in the hopper each time the wheel is rotated and raise them sufficiently to break up the arch or bridge.

The compartment 14 formed by the walls 20b, 23 and 23a forms a convenient storage place for various food products or different types of beverages, this compartment being so located as to be readily accessible from the door opening without permitting an undue rush or escape of cold air from the main bottle compartment.

The entire arrangement is such as to promote simplicity, both in construction and operation, while at the same time obtaining maximum refrigeration efficiency with a minimum of cold loss due to opening and closing of the door.

It will be understood that certain changes in construction and design may be adopted within the scope of the invention as defined by the appended claims. Moreover, it will be clear that certain cans, cartons and other objects may be

refrigerated within the described cabinet; hence, the references to "bottles" in the description and claims are not limitations but are merely descriptive and illustrative.

5. What is claimed is:

1. Bottle dispensing apparatus comprising a cabinet having a door opening and a refrigerated bottle storage compartment or chamber therein, deflector walls in said chamber arranged in opposed converging relation to cause the bottles to roll by gravity to a common hopper-like passage, a gravity runway having its receiving end communicating with said passage and its discharge end terminating adjacent the door opening, a door for said opening having means on the inner face thereof adapted to receive a bottle from said runway and carry it outwardly with the door when the door is opened, means operatively connecting said door with said wheel whereby each time the door is opened and closed said wheel is given a step-by-step rotary movement, and a separate storage compartment in said bottle storage compartment, the top wall of said latter storage compartment comprising one of said first-named defectors and the bottom wall of said latter compartment overlying said runway.

2. Bottle dispensing apparatus comprising a cabinet having a door opening and a refrigerated bottle storage compartment or chamber therein, an outer insulated wall and an inner casing or housing spaced from said wall and forming the side and bottom walls of said storage chamber, means within the lower region of said chamber providing a hopper-like passage terminating in a gravity runway adjacent the door opening, a rotary bottle dispensing wheel or magazine extending transversely across said hopper-like passage and when idle preventing the bottles in the storage compartment from moving into said runway, a door for said opening, an indexing disc mounted in the space between said casing and outer insulated wall and having an operative connection with said magazine wheel, and pawl and linkage mechanism operatively connecting said door with said disc whereby each time the door is opened and closed, the disc is actuated to thereby actuate the magazine wheel and effect delivery of a bottle from the storage compartment to the upper end of said runway.

3. A bottle cooler comprising a cabinet having insulated walls, a casing in said cabinet spaced from said walls and defining a storage compartment and hopper, said casing being formed of material of good heat conductivity such as sheet metal or the like, the bottom wall of the casing being shaped to provide a gravity runway or chute, the chute being of such dimensions as to permit passage of a succession of single bottles through to the discharge end of the chute, re

frigerating coils disposed between the outer insulated walls of the cabinet and said casing and in intimate relation with said chute and whereby bottles in said chute or runway are cooled by conduction and those in the hopper by convection, a door for the cabinet closing the discharge end of the chute so that when the door is opened the bottles in the chute are removable in sequence, and means to hold back all the bottles except the one at the discharge end of the chute.

4. A bottle cooler comprising a cabinet having insulated walls, a casing in said cabinet spaced from said walls and formed of sheet metal or like material having good heat conducting properties, said casing being shaped to provide a

chute or runway at the bottom of the compartment and a storage compartment and hopper thereabove, the chute being of such dimensions as to permit passage of a succession of single bottles through to the discharge end of the chute, means partitioning the chute from the storage compartment, refrigerating coils disposed in the space between the insulated walls and the casing and arranged to cool the bottles in the chute by conduction and those in the hopper by convection, bottle dispensing means interposed between the hopper and the chute for directing bottles one at a time from the hopper to the chute, a door in the cabinet closing the discharge end of said chute, and means mounted on the door adapted to pick up a bottle at the discharge end of the chute and move it out of the chute to a point where it may be removed by the user, the last named means being operable automatically upon opening of the door.

5. A bottle cooler comprising a cabinet having insulated walls, a casing of sheet metal or like material having good heat conducting properties disposed in said cabinet in spaced relation to said insulated walls providing a bottle storage compartment and hopper, the bottom of the casing being shaped to provide a chute or runway, the chute being of such dimensions as to permit passage of a succession of single bottles through to the discharge end of the chute, a supplemental cold storage compartment separating the chute from the storage compartment, refrigerating coils

disposed in the space between the insulated walls and said casing and arranged to cool the bottles in the chute by conduction and those in the hopper by convection, and a door in the cabinet located in a manner such that when it is opened it exposes the discharge end of said chute and also opens said supplemental storage compartment.

6. Bottle dispensing apparatus comprising a cabinet having a door opening and a refrigerated bottle storage compartment or chamber therein, an outer insulated wall and an inner casing or housing spaced from said wall and forming the side and bottom walls of said storage chamber, means within said storage chamber providing a hopper-like passage terminating in a gravity runway adjacent the door opening, a rotary bottle dispensing magazine extending across said hopper-like passage and when idle preventing the bottles in the storage chamber from moving into said runway, a door for said opening, an indexing member mounted in the space between said casing and outer insulated wall and having an operative connection with said magazine, and mechanism operatively connecting said door with said indexing member whereby each time the door is opened and closed the indexing member is actuated to thereby actuate the magazine and effect delivery of a bottle from the storage compartment to the upper end of said runway.

ROBERT WINTER HULL.
